UNITED STATES PATENT OFFICE

WILLIAM H. PULFORD, OF LIMA, OHIO, ASSIGNOR TO THE SCHAAF & GOOD COMPANY, OF FREMONT, OHIO, A CORPORATION OF OHIO

DESIGN FOR A HANDLE FOR TWEEZERS OR THE LIKE

Application filed May 2, 1932. Serial No. 43,686. Term of patent 14 years.

To all whom it may concern:

Be it known that I, WILLIAM H. PULFORD, a citizen of the United States, and a resident of Lima, Allen County, Ohio, have invented a new, original, and ornamental Design for a Handle for Tweezers or the Like, of which the following is a specification, reference being had to the accompanying drawing, forming a part thereof.

In the drawing, Fig. 1 is a plan view of a handle for tweezers or the like showing my new design, and Fig. 2 is a section taken on the line 2—2 of Fig. 1.

I claim:

The ornamental design for a handle for tweezers or the like, substantially as shown.

In testimony whereof I have hereunto signed my name to this specification.

WM. H. PULFORD.
